DESIGN FOR A GIFT BOX

David H. Holmes, Medford, Oreg., and Reginald Meller, Oakland, Calif.

Application August 3, 1940, Serial No. 94,202

Term of patent 7 years

To all whom it may concern:

Be it known that we, David H. Holmes and Reginald Meller, citizens of the United States of America and residents, respectively, of the city of Medford, State of Oregon, and of the city of Oakland, State of California, have invented a new, original, and ornamental Design for a Gift Box, of which the following is a specification, reference being had to the accompanying drawing, forming a part thereof, and in which—

We claim:

The ornamental design for a gift box, substantially as shown.

DAVID H. HOLMES.
REGINALD MELLER.
